CLAIM

The ornamental design for an inflatable float, as shown and described.

DESCRIPTION

FIG. 1 is a perspective view of an inflatable float showing the claimed design.

FIG. 2 is a top view of the inflatable float shown in FIG. 1.

FIG. 3 is a bottom view of the inflatable float shown in FIG. 1.

FIG. 4 is a left-side view of the inflatable float shown in FIG. 1, the right-side view being a mirror image thereof.

FIG. 5 is a front view of the inflatable float shown in FIG. 1; and,

FIG. 6 is a back view of the inflatable float shown in FIG. 1.

The broken lines in the figures show portions of the inflatable float that form no part of the claimed design.
